UNITED STATES PATENT OFFICE.

CLARENCE L. PATTERSON, OF DETROIT, MICHIGAN, ASSIGNOR TO METALWOOD MANUFACTURING COMPANY, OF DETROIT, MICHIGAN, A CORPORATION OF MICHIGAN.

FLUID-PRESSURE-TESTING MACHINE.

1,282,120.

Specification of Letters Patent.

Patented Oct. 22, 1918.

Application filed November 1, 1917. Serial No. 199,759.

To all whom it may concern:

Be it known that I, CLARENCE L. PATTERSON, a citizen of the United States of America, residing at Detroit, in the county of Wayne and State of Michigan, have invented 5 certain new and useful Improvements in Fluid-Pressure-Testing Machines, of which the following is a specification, reference being had therein to the accompanying drawings.

The invention relates to machines for applying internal pressure in the testing of the strength of hollow bodies, being more particularly designed for the testing of 15 shells for projectiles. The invention consists in the novel means employed for filling the hollow bodies with liquid and excluding all air or gas therefrom; further, in various features of construction as hereinafter set 20 forth.

In the drawings:

Figure 1 is a front elevation partly in section of the apparatus;

Fig. 2 is a sectional side elevation thereof;

Fig. 3 is an enlarged section through the high pressure sealing gap;

Fig. 4 is a horizontal section through the hollow presser head; and

Fig. 5 is a vertical section therethrough.

30 A is the frame for supporting the apparatus, comprising the bed or table A' and legs A'. B and B' are parallel rods or columns mounted in the bed or table A' and extending upward and downward therefrom.

35 C is a cross-head at the upper ends of the rods B B' and which carries the hydraulic cylinder D having a downwardly-projecting piston E which is connected with a cross-head F slidably engaging the rods B 40 and B'. G and G' are springs sleeved upon the rods B and B', their lower ends abutting against collars H and H' on said rods and their upper ends bearing against the cross-head F and yieldably pressing the same upward.

45 I is a cross-head at the lower ends of the depending portions of the rods B and B', which carries a hydraulic cylinder J having the upwardly-projecting piston K engaging a cross-head L slidable on said rods B and B'. M is a second hydraulic cylinder arranged below the cylinder J and having a downwardly-extending piston N engaging the cross-head O which is coupled by rods P and P' with the cross-head L.

The arrangement is such that the operation 55 of the piston K in the cylinder J will raise the cross-head L, while the operation of the piston N in the cylinder M will lower said cross-head.

The hollow bodies to be tested are arranged between the cross-head F and the bed A', being held in position by the pressure in the cylinder D operating upon the piston E and cross-head F. The testing pressure is developed by the upward movement of the cross-head L under the actuation of the piston K and the cylinder J, the construction of the apparatus for this purpose being as follows: Q is a high pressure chamber mounted on the bed A', and R is 60 a ram or piston operating in said cylinder and actuated by the cross-head L. The cross-sectional area of the piston R is small relative to the area of the piston K in the cylinder J, and consequently there will be a proportionately great multiplication of power 65 to produce the desired high hydraulic pressure in the cylinder Q. It is very essential to securely pack the piston so as to avoid leakage of the fluid, and it is equally important to form a tight seal between the hollow article to be tested and the upper end of the cylinder. Again it is important 70 that both the cylinder Q and the hollow article connected therewith should be completely filled with the liquid without entrapping any air or other elastic gas. These desired results I have obtained by immersing the cylinder and sealing head in a tank 75 of liquid which is of sufficient capacity to permit of filling the shells or hollow bodies therein, and without withdrawal of the same to place them in engagement with the seat. Thus, as shown, S is the tank which is mounted upon the bed or table A' to surround and to extend upward above the cylinder Q. At the front this tank has a depending portion S' of sufficient depth to completely immerse the shells or other hollow bodies to be tested and also of a width 80 which permits of turning the articles, while beneath the liquid, so as to maintain the mouth beneath the level of the liquid while engaging the same with the sealing seat. This sealing seat is preferably formed by 85 an annular member T, which is provided with a bead T' surrounding the mouth of the cylinder and engageable with the end 90 of the cylinder.

of the nose or bourrelet of the shell or other article to be tested. The member T is formed of hardened metal and the hardness is greater than that of the metal of the shell, 5 so that the bead T' will slightly indent or seat itself in the shell to form a complete seal. A ring U of softer metal surrounds the bead T' and operates as a guide for the bourrelet. Both of these parts are readily 10 detachable and reengageable and consequently whenever they become worn through use they may be replaced or re-ground. The joint between the member T and the cylinder Q is sealed by providing an annular 15 tongue T² on the member T engaging a corresponding groove in the member Q and bearing upon a gasket W therein. Y is a high pressure gage which is connected to an aperture Z in the cylinder Q, the connection being immersed in the tank S.

With the construction as described in operation, the shell or other article to be tested is first placed in the portion S' of the tank and is completely filled with liquid. It is 25 then inverted and drawn upward so that its open end while still beneath the level of liquid may be placed upon the gasket U on the seat T. Fluid under pressure is then admitted to the cylinder D, which will de- 30 press the piston E against the upper end of the shell, forcing the same to its seat and holding it there with sufficient pressure to more than counteract any upward pressure developed by the piston R. It is desirable 35 to test the strength of the ends of the shells as well as the cylindrical bodies thereof, and to permit of this a bearing block E' is ar- ranged between the piston E and the shell, said block having an annular seat portion 40 for engaging the marginal portion of the shell without supporting or bearing against the bottom thereof. The block E' is also cut away at E² sufficiently to permit of in- spection of the top of the shell while the 45 pressure is being applied thereto. To permit of uniform distribution of pressure on the shell the block E' preferably has its upper end of segmental spherical form and engag- ing a corresponding bearing upon the lower 50 end of the piston E, thereby permitting a slight rocking for the distribution of the pressure.

After the shell is forced to its seat and held by the pressure in the cylinder D, fluid 55 is admitted to the cylinder J, which, operating against the piston K, will move the same upward, carrying with it the cross-head L and piston R. The latter will apply the pressure to the fluid within the high 60 pressure chamber Q which is in direct communication with the interior of the shell and consequently the desired pressure may be applied; this being indicated by the gage Y. As soon as the test is completed the pressure 65 of the piston R is relieved, which is accom-

plished by admitting fluid to the cylinder M to operate upon the piston N, which through the rods P and P' will draw upon the cross-head L and depress the piston R. This positive means of disengagement is de- 70 sirable as the friction produced by the pack- ing about the piston R will interpose con- siderable resistance to the movement there- of. Pressure in the cylinder D is then re- lieved, permitting the springs G and G' to 75 raise the cross-head F, which permits of re- moving the shell from its seat and placing another shell to be tested in engagement therewith. The tested shells when removed from the tank will empty the liquid back 80 thereinto, and in this way the filling and the emptying is expeditiously performed.

My construction has many advantages, first, in the development of the high pres- 85 sure adjacent to the point of application to the seat for the shell. This avoids heavy construction and difficulty in securing per- fect sealing of high pressures incident to the development of the pressure at a more re- 90 mote point. Another advantage is the test- 95 ing of the shell in inverted position and with the bearing for the upper end cut away for the double purpose of exposing this end to the testing pressure and for observation to detect any defects. A still further advan- 100 tage is the arrangement of the tank on the bed or table for the filling and emptying of the shells, which avoids the slopping of the water over the mechanism and renders it possible for a single operator to easily ma- 105 nipulate the machine.

What I claim as my invention is:

1. In a testing machine, the combination 105 with a chamber and a member movable therein to develop high pressure, of an an- nular seat for the hollow article to be tested in connection therewith, said seat having an opening therethrough directly communicat- 110 ing with said chamber, means for rigidly holding the article upon said seat, and means for surrounding said article and seat in the sealing fluid.

2. In a testing machine, the combination 115 with a chamber and a member movable therein to develop high pressure, of an an- nular seat for the hollow article to be tested in connection therewith, said seat having an opening therethrough directly communicat- 120 ing with said chamber, and a fluid holding receptacle surrounding said seat and per- mitting of the immersing and filling of the hollow articles therein and of the movement of said articles into engagement with said seat.

3. In a testing machine, the combination 125 with a high pressure chamber open at its upper end and having an annular seat for the hollow article to be tested surrounding said opening, of a fluid container surround- 130 ing said seat and permitting of the immers-

ing, filling and reversing of the hollow articles to be tested, and the movement of the same with the mouth below the level of the liquid into engagement with said seat.

5 4. In a testing machine, the combination with a high pressure chamber having an opening at its upper end and an annular seat for the hollow article to be tested surrounding said opening, of a fluid container surrounding said seat and permitting of the immersion, filling and reversing of the hollow articles to be tested and movement of the same while the mouth is still immersed into engagement with said seat, hydraulic 10 means for holding the article to be tested in engagement with its seat, a piston in said high pressure chamber, and means for moving said piston upward to develop the desired internal pressure in said cylinder and 15 connected hollow article.

20 5. In a testing machine, the combination with means for developing high fluid pressure, of an annular seat for the hollow article to be tested in connection with said fluid pressure developing means, means for rigidly holding the article to be tested upon said seat, and a fluid container surrounding said seat, the level of the liquid within said container being above the seat to immerse 25 the mouth of the hollow article while engaged with the seat.

30 6. In a testing machine, the combination with high fluid pressure developing means and an annular seat for the hollow article to be tested in communication therewith, of means for holding said article to its seat, said means engaging the margin only of the closed end portion of said article and exposing said end portion to observation.

35 40 7. The combination with high fluid pressure developing means and an annular seat for the article to be tested in connection therewith, of a hydraulic press for holding the hollow article to be tested to said seat, and a block through which the pressure is applied to said article having an annular marginal bearing thereon and rockable in relation to said hydraulic press to uniformly 45 distribute the pressure through said bearing 50 to the article.

55 8. In a testing machine, the combination with an annular seat for the open end of the hollow article to be tested, of a container surrounding said seat and provided with liquid for immersing the same, means for holding said hollow article to the seat, and a ram or piston for directly applying pressure to the fluid within said seat and hollow body to develop high pressure therein.

60 65 9. In a testing machine, the combination with an annular seat for the hollow article to be tested, of a container surrounding said seat and provided with liquid for immersing the same, said container permitting of the immersion and filling with the liquid of the

hollow articles to be tested, a pressure gage connected with said seat, means for holding the filled hollow articles to be tested to the seat, and a ram or piston for directly applying pressure to the liquid within said seat 70 and hollow article to develop high pressure therein.

10 4. In a testing machine, the combination of a hollow head or cylinder, a removable and replaceable annular seat engaging said head or cylinder, a tank for containing liquid surrounding and immersing said seat, means for holding the hollow article to be tested to said seat, and a plunger or piston slidable in said hollow head for directly 75 pressing on the liquid within said seat and hollow article to develop high pressure.

11 5. In a testing machine, the combination with an annular seat for the hollow article to be tested and means for developing high 80 fluid pressure through the opening in said seat, of means for holding the article to its seat including a bearing member engaging the marginal portion only of the end of said hollow article and cut away for observation 85 of the central portion of said end.

12 6. In a testing machine, the combination with a high pressure chamber, having an annular seat for a hollow article to be tested, of a fluid container surrounding said seat and 90 communicating with said chamber through an opening in said seat, said container permitting of the immersing and filling of the hollow articles to be tested, and allowing movement of the same while the mouth of 95 the article is still immersed into engagement with said seat, hydraulic means for holding the article to be tested in engagement with its seat, a piston in said high pressure chamber, and means for moving said piston upward to develop the desired internal pressure 100 in said chamber and connected hollow article.

13 7. The combination with high fluid pressure developing means, and an annular seat 110 for the article to be tested in connection therewith, of means for applying pressure to the hollow article to be tested to maintain the same upon its seat, and a block through which the pressure is applied to said article 115 having an annular marginal bearing thereon and rockable in relation to said pressure applying means to uniformly distribute the pressure through said bearing to the article.

14 8. In a testing machine, the combination with high fluid pressure developing means, and an annular seat for the hollow article to be tested in communication therewith, of hydraulic means for holding said article to its seat, said means engaging the margin 120 only of the closed end portion of said article and exposing said end portion to observation.

15 9. The combination with high fluid pressure developing means, and an annular seat 125

for the article to be tested in connection therewith, of a press for holding the hollow article to be tested to said seat, and a block through which the pressure is applied to said article having an annular marginal bearing thereon, and rockable in relation to said press to uniformly distribute the pres-

sure through said bearing to the article, said block having a central recess and lateral side openings in communication with said recess to permit of observation of the engaged article.

In testimony whereof I affix my signature.
CLARENCE L. PATTERSON.
